UNITED STATES PATENT OFFICE

170,935

KNIFE SHARPENER

Joseph Palma, Jr., Berwyn, Ill., and Courtney A. Leubner, Milwaukee, Wis., assignors to G. M. Laboratories Inc., Chicago, Ill., a corporation of Illinois

Application July 9, 1953, Serial No. 25,855

Term of patent 14 years

(Cl. D37—1)

To all whom it may concern:

Be it known that we, Joseph Palma, Jr., and Courtney A. Leubner, citizens of the United States and residents, respectively, of Berwyn, Cook County, State of Illinois, and Milwaukee, Milwaukee County, State of Wisconsin, have invented a new, original, and ornamental Design for a Knife Sharpener, of which the following is a specification, reference being had to the accompanying drawings, forming a part thereof.

Fig. 1 is a front elevational view of a knife sharpener, showing our new design;

Fig. 2 is a top plan view thereof;

Fig. 3 is a rear elevational view thereof;

Fig. 4 is a right end elevational view of Fig. 1; and

Fig. 5 is a left end elevational view of Fig. 1.

We claim:

The ornamental design for a knife sharpener, as shown.

JOSEPH PALMA, JR.
COURTNEY A. LEUBNER.
